UNITED STATES PATENT OFFICE

2,557,017

REDUCING PAPER TUBES IN DIAMETER

William F. Stahl, Kenilworth, Ill.

Application October 1, 1945, Serial No. 619,544

3 Claims. (Cl. 93—1)

1

This invention relates to reducing a paper tube in diameter and more particularly to the reducing in diameter of laminated or spirally wrapped paper tubes. In the practice of the invention a portion only of a tube may be reduced so that the finished tube has a portion of larger diameter and a portion of reduced diameter.

Laminated paper tubes are ordinarily formed by wrapping an adhesive covered paper strip spirally upon itself to form a tube. The tube may then be cut in the various lengths and fashioned into different types of products, such as cores for windings of insulated wire, etc. For some uses, it is important to have an integral tube having one portion thereof relatively large and another portion of reduced diameter. Attempts to reduce the diameter of a paper tube have resulted in an unsightly and extremely weak structure. In the reduction of the diameter of the tube through pressing, wrinkles or creases are formed in all directions, and the resulting structure is extremely fragile.

An object of the present invention is to provide a simple method by which a portion of a laminated paper tube may be quickly reduced in diameter while at the same time remaining relatively strong and having a smooth exterior. A further object is to provide a method whereby a spirally wrapped paper tube may be reduced in diameter in such a manner as to cause the creases or wrinkles therein to run uniformly in a longitudinal direction thereby reinforcing the structure against transverse bending and also providing over the longitudinal creases and wrinkles a top skin or layer which is relatively free from wrinkles and which forms with the longitudinal creases and ribs a sturdy product. Another object is to provide an improved paper tube having a portion of relatively large diameter merging with a portion of relatively small diameter, the portion of relatively small diameter, together with the connecting portion, being reinforced with an outer skin portion which combined with the longitudinal creases in the body of the reduced portion of the tube results in a tube of relatively strong cross section. Other specific objects and advantages will appear as the specification proceeds.

The invention is illustrated, in a preferred embodiment, by the accompanying drawing, in which—

Figure 1 is a perspective view of a tube product formed in accordance with my invention; Fig. 2, a longitudinal sectional view of the structure shown in Fig. 1; Fig. 3, a side view in ele-

5 vation, and partly in section, of apparatus employed in the carrying out of my new method, a portion of a paper tube being shown on the apparatus and in position prior to the reducing operation; Fig. 4, a view similar to Fig. 3 but showing the tube in reduced condition after the spinning operation; Fig. 5, a greatly enlarged plan view of a small part of the inside of the reduced portion of the tube 12; and Fig. 6, a greatly enlarged cross sectional view of a portion of the tube, the section being taken as indicated at 6—6 of Fig. 5.

In the illustration given in Figs. 3 and 4, 10 designates a mandrel which may be maintained in fixed position. The mandrel is provided at its forward end with an inwardly stepped portion 11 receiving the spirally wrapped paper tube 12. If desired, the member 10 may be provided with a further reduced portion 13. 14 designates the rotatable chuck in which is secured a spinning tool 15. The tool 15 is hollow in its forward portion and provided at its front with a bevel 16 which may be of any suitable angle. In the illustration given, the angle of the bevel is approximately 30° and, in common practice, such an angle has been found very satisfactory. It will be understood, however, that considerable variation in the angle may be made in the handling of different qualities of paper tube stock.

30 In the operation of the structure shown in Figs 3 and 4, the operator places the tube 12 in position upon the reduced portion 11, as shown in Fig. 3, and then while holding his finger upon 35 the end portion of the tube near the body 10 in order to prevent rotation of the member 12, the chuck 14 is advanced while it is being rapidly rotated. This movement brings the beveled edge 16 into contact with the forward end of the tube 12. Under the rapid rotation of the member 15, the tube 12 is reduced in diameter at its forward end and a product like that shown in Fig. 4 results from the operation. The rapid spinning of 40 the member 15 produces considerable heat, and the heat is effective also in producing the smooth exterior of the tube.

45 Under the effect of the rapidly rotating member 15 as the beveled edge 16 advances against the tube 12, there is formed in the body of the tube 12 a number of longitudinal channels or creases or wrinkles 17, as indicated more clearly in Fig. 5, running lengthwise of the tube. There are relatively no creases or wrinkles which extend in directions other than the longitudinal direction indicated. The result of the forming

2

of such longitudinal creases is to increase the strength of the tube against transverse strain. In addition to the forming of the creases in the body of the material, the ironing effect of the rotating member 15 produces a smooth skin portion 18 on the outer surface of the tube. The skin 18 bridges the longitudinal wrinkles or creases or ribs and provides a relatively smooth outer surface. The enveloping of the ribbed structure by the smooth skin body 18 produces a resultant tube structure highly resistant to transverse strain and to longitudinal strain. I do not know all the factors that enter into the forming of the new skin surface; the heat generated through the rotation of the member 15 seems to give a glazing effect which unifies the outer surface while at the same time the ironing effect of the member 15 seems to bring about a rematting or change of direction of the fibers, so that they substantially bridge the grooves or creases to provide an outer skin that is relatively free of wrinkles and extremely smooth.

In the structure shown in Fig. 1, the tube 12 is provided with a reduced portion 12a and the ends of the tube are pressed inwardly at 19 to lock the disks 20 in position. The foregoing structure is merely illustrative of one use to which the tube, having different diameters, may be put. It will be understood that such a tube having two portions of varying diameter may be employed in a great variety of products.

In the construction of the member 15 and particularly the beveled edge 16, it is important to use a high speed tool steel, and I prefer a highly polished tool steel. Such a tool operates effectively in reducing the diameter of the tube while at the same time rematting the fibers and producing a truly round reduced tubular portion of a glazed or shiny surface. It will be noted as indicated in Figs. 3 and 4 that the reduced diameter of the tube may be brought about without employing an inner support for the reduced portion. The spinning edge 16 which is gradually pressed against the tube is effective in itself in producing the reduced diameter of the tube and its new physical structure.

While in the foregoing specification, I have set forth certain details of structure and method for the purpose of illustrating one mode of the invention, it will be understood that such details may be varied widely by those skilled in the art without departing from the spirit of my invention and further that the claims herein should be

looked to as definitive of the scope of the invention.

I claim:

1. The method of reducing the diameter of a portion of a paper tube, comprising rotating a tubular edge having a diameter less than that of the tube and with an enlarged beveled mouth against said tube to reduce the diameter of the tube while forming longitudinally-extending valleys therein, and supporting the inner walls of the tube against rotation about the point of junction between the tube portions of different diameters while the beveled mouth of said edge irons the supported connecting portion between said tube portions of different diameters.

2. In a method for reducing the diameter of a portion of a laminated paper tube, the steps of pressing a longitudinal portion of the tube inwardly to reduce the diameter thereof and while forming longitudinal valleys therein, supporting against rotation the inner walls of the tube about the point of junction between the tube portions of different diameters, and simultaneously ironing the tube portion of reduced diameter to form thereon a smooth outer tube portion free of valleys.

3. In a method for reducing the diameter of a portion of a laminated paper tube, the steps of pressing a longitudinal portion of the tube inwardly to reduce the diameter thereof and while forming longitudinal valleys therein, supporting against rotation the inner walls of the tube about the point of junction between the tube portions of different diameters, and simultaneously ironing the tube portion of reduced diameter and the connecting portion joining it to the tube portion of larger diameter to form a smooth outer tube portion free of valleys.

WILLIAM F. STAHL.
